(57) **CLAIM**

The ornamental design for an automobile, as shown and described.

DESCRIPTION

FIG. 1 is a front view of an automobile showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof; and

FIG. 7 is a front perspective view thereof; and,

FIG. 8 is a rear perspective view thereof.

In the drawings, shading shown on a surface of the present design represents a three-dimensional shape of the surface.
